UNITED STATES PATENT OFFICE.

ALBERT SCHMIDT, OF DETROIT, MICHIGAN, ASSIGNOR TO FISHER BODY CORPORATION, OF DETROIT, MICHIGAN, A CORPORATION OF NEW YORK.

CURTAIN-ROD SUPPORT.

1,352,479.

Specification of Letters Patent. Patented Sept. 14, 1920.

Application filed November 25, 1918. Serial No. 283,982.

To all whom it may concern:

Be it known that I, ALBERT SCHMIDT, a citizen of the United States, residing at Detroit, county of Wayne, State of Michigan, have invented a new and useful Improvement in Curtain-Rod Supports, of which the following is a specification.

This invention relates to curtain supports for doors. These are not broadly new as a good many curtain supports for detachably fastening to the doors of automobiles are already in use. These, however, require the fastening or unfastening of some device before the curtain support can be put in place or detached. It is the object of this invention to provide a hidden socket and at the same time a very simple form of support which may be attached to the door or detached without the manipulation of any other member.

In the drawings,

Figure 1 is an inside elevation, fragmentary in character, of the door, door curtain and curtain support.

Fig. 2 is a fragmentary vertical section of the door showing the curtain rod in its socket.

Fig. 3 shows the mortise made in the doors to receive the socket fixture.

Fig. 4 is a section on the line 4-4 of Fig. 1.

A common method of attaching these curtain supports to the door is to slot the curtain support and have screws that screw through the slot and into sockets in the door. This makes a rather untidy appearance and it requires the application of a tool before the curtain rod can be attached or detached and also interferes with the trimming. It is the object of this invention to do away with this unsightliness and at the same time afford a rod which can be attached and detached without a tool so that the curtain and rod can be placed and disposed with practically as much ease as the ordinary storm curtains. This is accomplished by the fixture and the rod now to be described.

The rod is simply a piece of stock of circular cross section that is bent to form the vertical curtain supporting section *a*, angles across the top edge of the door at *b* and is

provided with a lower section *c* bent on a true arc of the same radius at all points, tapered at the end *x*.

The socket member is formed by the concave face plate *d* and the concave rear plate *e* of semi-cylindrical cross section. The flanges of the concave face plate fold over the flanges of the rear plate, as shown in Fig. 4, and screws *f* pass through these flanges to secure the socket in the concave mortise *g* made in the door frame. This socket has a turned-up lug *h* at the bottom which serves as a stop for the end of the curtain rod. This socket has an arc struck on the same radius as the arc section of the curtain support and is arranged to fit the curtain support fairly tightly so as to prevent all rattling, due to tapering of socket and rod.

Now obviously this curtain rod can only be taken out of the socket by a turning movement on an axis coincident with the center of the arc that describes the section *c*. Obviously the door when closed will cause the door curtain to bear against adjacent portions of the top or adjacent side curtains which act as jams. The top itself tends to prevent any of this turning movement if the jarring of the car overcomes the weight of the curtain and curtain rod so as to tend to force it out. Hence when traveling along the road the top coöperates to keep the curtain rod in place while when in a stationary position the door is opened the gravity will keep the curtain rod in place. One can easily appreciate how easily the curtain and rod may be detached from the door simply by opening the door and turning the rod out. The arc socket makes twisting of the rod impossible.

One of the very marked advantages of this construction is that everything but the escutcheon *i*, which is screwed over the upper opening in the rear plate and onto the door frame, is concealed under the trimming *k* when the door has been finished.

The rod itself is made out of common rod stock bent to the proper shape so that it is the cheapest possible construction. Storage place can be afforded in the car to take care of both the rod and the curtain so that the curtain can be put up just as easily as any

of the other curtains, which is not the case with any prior construction with which I am familiar.

The angular position of the curtain supporting section *a* on the rod can be easily regulated by the position of the stop *h*.

What I claim is:

1. A door curtain fixture, having in combination, a socket member which can be secured to the door and which has a relatively long recess formed on an arc, and a curtain rod whose lower end is formed on the same arc to turn in and be capable of being held in said recess of the socket member without other fastening means.

2. A door curtain fixture, having in combination, a socket member built to be secured to a vehicle door and provided with a relatively long recess formed on a true arc, a door curtain rod having upright curtain-supporting portions, an angular portion, and a lower arc section adapted to fit in the arc recess of the socket member and capable of being supported solely by said relatively long recess.

3. A door curtain fixture, having a socket member formed of plates forming an opening and arranged to be secured to a vehicle door, said plates forming an arc-like passage-way relatively long and which terminates at the bottom in a rest, and a door curtain rod having a curtain-supporting section and a lower section formed on an arc

to engage in said socket by a turning movement on an axis coincident with the center 35 on which the arc is struck, said rod being capable of being supported solely by said relatively long arc-like passage-way.

4. A curtain support, comprising a socket member formed by a front and rear plate 40 forming an arc-like passage-way and arranged to be secured to the inside of a vehicle door, and a curtain rod having a curtain supporting section and a lower arc section adapted to turn into the passage-way 45 in the socket member on a turning movement coincident with the center on which the arc-like passage-way of the socket is struck.

5. A curtain support, having in combination, a socket member having a relatively long and small passage-way which has both a vertical and lateral direction, and a curtain rod having an upright curtain supporting portion and a lower portion, the latter 55 formed to fit nicely into the said passage-way and to follow the directions of the passage-way and which requires both a lateral and a vertical movement to locate the curtain rod in the socket or take it from the 90 socket, whereby the rod may be adequately supported solely by the lower part resting in said passage-way.

In witness whereof I have hereunto set my hand on the 19th day of November, 1918. 95

ALBERT SCHMIDT.
